UNITED STATES PATENT OFFICE

EDWARD N. JAMES, OF DAYTON, OHIO, ASSIGNOR TO FRIGIDAIRE CORPORATION, OF DAYTON, OHIO, A CORPORATION OF DELAWARE

REFRIGERATING APPARATUS

Application filed January 9, 1929. Serial No. 331,288.

This invention relates to refrigerating apparatus and particularly to an improved construction of evaporators for such apparatus.

- 5 15 One of the objects of the invention is to provide an improved evaporator construction which is simple and economical to build, and which is light without sacrificing sturdiness or strength.
- 10 Another object is to provide an improved form of evaporator container having means for confining a plastic gasket between the container and its closure to prevent undue mashing or thinning of the gasket.

- 15 20 More specifically it is an object of the invention to provide an improved connection between the evaporator container and removable cover which will effectively prevent water from freezing between the container and the cover.

Still another object is to provide an improved construction which does not depend upon soldering or welding to form either a mechanical connection or a fluid seal between

- 25 parts.
- Further objects and advantages of the present invention will be apparent from the following description, reference being had to the accompanying drawing, wherein a preferred form of the present invention is clearly shown.

The single figure of the drawings is a vertical longitudinal section of a portion of a refrigerating evaporator embodying the invention.

Refrigerating evaporators including a header forming a reservoir for liquid refrigerant, a number of loops of tubing joined to the header for circulating refrigerant, and 40 a removable closure plate for the header carrying a float-controlled valve for regulating the quantity of liquid refrigerant in the evaporator, have heretofore been made, an example of such general construction being shown in the application of Otto M. Summers, Serial No. 266,397, filed March 31, 1928. It has been the custom to construct the headers of these evaporators of a drawn metal shell, usually of brass. Because the closure 45 plate carries a number of quite heavy valves,

its construction must be necessarily heavy, and because this heavy assembly of plate valves must be removably secured to the thin sheet metal shell it is necessary to provide a very substantial anchoring device to 55 which the plate may be secured. It has been customary to form this anchoring device as a heavy forged brass ring or doughnut which is soldered in the end of the shell and provided with tapped holes for receiving bolts 60 for securing the header in place. This type of construction has necessarily resulted in an extremely heavy evaporator and one which has been expensive to manufacture. Another undesirable feature of evaporators 65 of this type is that the soldered connection of the shell to the ring is subject in certain instances to electrolytic decomposition. Furthermore it has been found that during operation water will condense on the evaporator and collect in the crevice between the plate and the ring outside of the usual sealing gasket. This water freezes in the crevice and damages the evaporator.

My invention is concerned among other 70 things with overcoming the above-mentioned disadvantages in prior constructions.

Referring to the drawings 10 designates a cylindrical sheet metal shell forming the main body of the header to which are connected a 75 number of tubes 11 for circulating refrigerant. The particular method of connecting the tubes is not shown herein but a solderless mechanical connection is preferred such as is shown in the application of Otto M. Summers for refrigerating apparatus, Serial No. 322,749, filed November 30, 1928. The open end of the shell or body of the header is formed into a flange 12 which projects outwardly substantially at right angles to the 80 cylindrical wall. The outer edge of the flange is turned into a cylindrical lip 14 which is substantially perpendicular to the flange and hence parallel to the wall 10. A circular plate 16 forms a closure for the container or header 85 and is secured thereto by means of bolts 18 which pass through the plate 16 and flange 12. The bolts are threaded into a reinforcing ring 20 which surrounds the cylinder 10 adjacent the flange 12. The ring 100

20 is relatively thick and rigid so as to form a substantially rigid plane member for clamping the flange to the plate 16. A plastic gasket 22 made of material such as lead, or 5 an alloy of 50% lead and 50% tin is placed between the cover plate or head and the flange 12 to seal the joint between them.

Since the gasket may flow considerably when pressure is exerted by the clamping 10 bolts, means is provided for preventing the gasket from flowing out from between the flange and the plate. The lip 14, above referred to, confines the gasket at its outer edge, the plate 16 being of such a size as to fit 15 fairly accurately within the lip 14 and prevent outward flow of the gasket. Inward flow of the gasket is prevented by the flange or boss 24 which is formed in the header 16 and fits within the shell 10. The lip 14, in 20 fitting over the plate 16 prevents any crevice between the plate 16 and flange 12 which might receive water condensed on the evaporator.

The cover plate 16 may be formed in any 25 suitable manner as by casting, forging or punching, but I prefer to use the punched form of plate as shown in the drawings. The head plate is provided with a pair of openings 26 and 27 into which are soldered, 30 brazed, welded or otherwise secured bosses 28 and 29 respectively for receiving an outlet valve 30 and an inlet valve 31. The inlet valve boss 29 is threaded internally as shown to receive a screw-threaded portion 32 of the 35 inlet valve 31. The outlet boss 28 is provided with a number of tapped holes 33 which receive bolts 34 for clamping the outlet valve housing 30 to the boss. Any suitable gasket 35 is used to seal the connection between the 40 outlet valve and the boss 28, such gasket being confined between shoulders 36 on the boss and 37 on the housing.

The inlet valve housing is threaded into 45 the inlet boss 29 by means of the tapered thread shown, which forms an effective seal as is well-known. Since the presence of the inlet valve prevents the rotation of the outlet valve in the opening in the boss 28 (which would be necessary for a similar method of 50 attachment) the outlet valve housing must be secured to the plate by means such as bolts 34 which require no relative movement between the head and valve.

A float supporting bracket is attached to 55 the inlet boss 29 within the header 10. This bracket consists of a pair of arms 40 integrally formed with a pair of arms 42. The latter fit about the boss 29 and are clamped thereto by means of the bolt 43 which preferably lies 60 in a recess 44 and thus prevents rotation of the bracket about the boss or slipping of bracket along the boss. A float arm 46 is mounted between the arms 40 upon a pivot 47 and carries a float 48. The arm 46 is provided with a stop 49 which strikes the abut-

ment 50 formed integrally with the arms 40 and 42 and thus limits downward movement of the float. The float arm 46 carries a loosely pivoted needle valve 52, the end of which is disposed in an opening 53 in the inlet boss 29, said opening forming a guide for the needle valve. The valve seats against the valve seat 54 adjacent the duct 55 which conveys liquid refrigerant from the inlet valve 31 to the interior of the header.

The needle valve is opened and closed in accordance with the position of the float 48 to maintain a substantially constant quantity of liquid in the header as is well known.

To the inside of the outlet boss 28 is attached an outlet tube 60 whose mouth or entrance 61 is disposed parallel to the liquid level and at a considerable distance above it. Below the outlet 61 are one or more oil drain holes 62 while the baffle 63 is placed below 85 the outlet tube 60 to prevent liquid refrigerant from splashing into the outlet tube.

While the form of embodiment of the invention as herein disclosed, constitutes a preferred form, it is to be understood that other 90 forms might be adopted, all coming within the scope of the claim which follows.

What is claimed is as follows:

In an evaporator for refrigerating apparatus of the type having a container forming a reservoir for volatile liquid refrigerant, an integral drawn sheet metal shell comprising a portion forming a container; a flange projecting perpendicularly outward from the container for receiving a plastic gasket and a lip projecting substantially perpendicularly from the flange for confining the gasket within the flange; a plastic gasket disposed adjacent the flange within the lip, a closure for the container adjacent the gasket, the closure having a shoulder disposed inside of the gasket and flange whereby the gasket is completely enclosed between the closure, flange and lip, a reinforcing ring on the opposite side of the flange from the gasket, and bolts 100 passing through the gasket and flange and engaging said ring to form a sealed joint between the closure and the container.

In testimony whereof I hereto affix my signature.

EDWARD N. JAMES.
